P. N. HOOPER

SPOUT

Filed Jan. 26, 1921

FIG. 3.

5

FIG. 2.

FIG. 1.

Percy N. Hooper ^{INVENTOR}

by *James L. Morris*

attorney.

UNITED STATES PATENT OFFICE.

PERCY NICHOLAS HOOPER, OF LONDON, ENGLAND.

SPOUT.

Application filed January 26, 1921. Serial No. 440,074.

To all whom it may concern:

Be it known that I, PERCY NICHOLAS HOOPER, a subject of the King of Great Britain, residing at London, England, have 5 invented new and useful Improvements in Spouts, of which the following is a specification.

This invention relates to improvements in spouts or like pouring orifices for oil cans 10 and like liquid containers, more especially cans or containers of rectangular or cylindrical form with flat heads having the spouts or pouring orifices set near to the edges of such heads. In cans or containers 15 of this kind the spout or pouring orifice is usually a separate part which is soldered, spun or otherwise fixed in an aperture in the head of the can.

According to this invention a tubular 20 part is slidably mounted in the above mentioned spout or pouring orifice fixed in the head of the can so that it can be pushed into the can into a position in which it projects only slightly, if at all, outside of the 25 fixed spout or pouring orifice, and so that it can be drawn out to act as a pouring spout or nozzle of which the mouth is at an appreciable distance away from the head of the can, according to the length of such 30 slidable part. A packing material of a suitable kind is inserted between the fixed spout and the said slidable part which is guided therein and provided with flanges at its ends to prevent it from being entirely 35 drawn out of its guide in either direction.

This construction provides a long spout which, under ordinary circumstances, is stowed within the can but which, when occasion arises, can be drawn out to enable 40 the contents of the can to be poured directly therefrom into an oil cup or feed reservoir situated in such a position that the can cannot be brought close to the filling opening thereof. When the tubular part is so 45 drawn out from the can and inserted in the filling opening of the oil cup or feed reservoir which is to be replenished, the can may be tilted to the required angle without spilling of the contents of the can.

50 In the accompanying drawings:—

Figure 1 is a view in section of part of a can fitted with the improved arrangement of spout according to this invention, showing the slidable tubular part stowed within 55 the can.

Figure 2 is a sectional view of a cap for closing the said spout.

Figure 3 is a view similar to Figure 1, showing the slidable tubular part in side elevation and in its extended position. 60

Referring to the drawing, 1 is the head of a can and 2 is the usual spout, the lower flared end of which is inserted in a groove or bead on a plate 3 which, with the spout, is then soldered to the head 1. This fixed spout 2 is preferably screw threaded to receive a cap 4. A tubular part 5 is mounted to slide within the spout 2, a piece of packing material 6 being inserted in the spout between the spout and the tubular part 5 and held in place between the inturned upper end 7 of the spout 2 and the plate 3 which also has an opening of the same shape as the tubular part 5 to receive and form a guide for the part 5. The rims or lips surrounding the openings in which the tubular part 5 is guided are curved in cross-section, as shown in Figs. 1 and 3. When the part 5 is in the position shown in Figure 1, the cap 4 can be screwed on to the fixed spout 2 to close the latter, a washer or disc 8 within the cap being compressed on to the edge of the spout, the part 5 and packing 6 being then entirely shut in beneath this cap. The accumulation of dust or dirt on any lip or part over which the liquid flows when being poured out is thus prevented. 75

When the cap 4 is removed the tubular part 5 can be drawn out to the position shown in Figure 2. A bar 9 or other suitable means may be provided within the tubular part 5 so as to be grasped by the fingers or taken hold of by a suitable implement in order to draw the tubular part 5 outwardly. The part 5 is preferably flanged or flared at both ends after it has been placed in position in the spout 2, to prevent it from being drawn completely out of the spout in either direction. 80

I claim:—

1. The combination with the head of a can, of a plate having a central opening therein, a lip curved in cross-section bounding the said opening, a spout having one end seated on the said plate and having at its other end an internal flange provided with a lip curved in cross-section, a tubular part slidably mounted in the openings bounded by the said curved lips, and a bar mounted within the said tubular part adja- 105 110

cent to one end thereof accessible from outside the can.

2. The combination with the head of a can, of a plate having a central opening therein, a lip curved in cross-section bounding the said opening, a spout having one end seated on the said plate and having at its other end an internal flange provided with a lip curved in cross-section, said spout having

10 screw threads formed on its exterior to receive a cap, and a tubular part slidably mounted in the openings bounded by the said curved lips.

PERCY NICHOLAS HOOPER.
